UNITED STATES PATENT OFFICE.

HAROLD E. YARROW, OF GLASGOW, SCOTLAND.

STORAGE OF OIL-FUEL IN VESSELS.

1,296,449.

Specification of Letters Patent. Patented Mar. 4, 1919.

Application filed October 30, 1917. Serial No. 199,314.

To all whom it may concern:

Be it known that I, HAROLD EDGAR YARROW, a subject of the King of Great Britain, residing in Glasgow, Scotland, have invented certain new and useful Improvements Connected with the Storage of Oil-Fuel in Vessels, of which the following is a specification.

In certain classes of vessels using oil fuel, 10 more particularly in destroyers, it is important to increase the storage capacity for the oil beyond that usually provided. If this additional storage space were provided at the ends of the vessels the amidships part 15 would require to be very considerably strengthened in order to stand the stresses set up when the ends were raised out of the water in a heavy sea.

In addition to the tanks usually provided, 20 other oil tanks may be placed amidships underneath the boilers throughout the stokehold compartments. This disposition of the weights reduces the stresses acting on the vessel in a seaway and thereby enables material to be economized and a saving in weight to be effected.

In order to insure that the temperature of the oil shall not be unduly raised by the heat radiated from the brick pans at the 30 bottom of the furnaces, according to the invention, the air supply for some or all of the oil burners is led from the back of the boilers along a duct, the upper side of which is, preferably, formed by the brick pan and 35 the lower side by the top of the oil tanks. The arrangement has the advantage that the more the boiler is forced, the greater will be the quantity of air drawn past the oil tanks, so that the cooling effect will increase with the heat radiated from the brick pan.

In the accompanying drawing, Figure 1 is a cross section through a destroyer taken in front of one of the boilers. Fig. 2 is an 45 elevation partly in section through one of the boilers.

A is a steam drum, B water drums, C superheater tubes, D is the front of an air casing; E¹, E² are oil fuel sprayers and 50 F¹—F⁴ non-return flaps admitting air to the

casing surrounding each sprayer; G are oil fuel tanks extending underneath the boilers; H is a duct between the bottom of the brick pan K and the oil tanks G, and through this duct air is led, in the example shown, to the four lowest oil fuel sprayers. H¹ is an extension of the air duct which may or may not be provided at the back of the boiler and leads to the stokehold. The duct H leads into an air space formed between the casing 60 D and an outer casing I, in which a door J is provided to give access to the oil sprayer E². L¹ is a lever with a handle at one end and a catch at the other for locking the air flap F³. L² is a lever provided with a screw 65 thread by which the air flap F⁴ is locked when the lever is screwed inward.

Air may be supplied from the duct to any number of sprayers, more or less than those shown; the air for the remaining sprayers is 70 taken directly from the stokehold in the usual manner.

Although to save weight it is preferable that the upper and lower parts of the air duct should be formed by the brick pan and 75 oil tanks respectively, thin plating may be used for the purpose.

Having thus described the nature of the said invention and the best means I know of carrying the same into practical effect, I 80 claim:—

1. In ships in which oil tanks are placed amidships below the boilers, means for preventing the tanks from attaining an undue temperature, comprising a duct between the 85 brick pan and the top of the tanks, through which duct air passes to a casing surrounding some or all of the oil fuel sprayers.

2. A duct according to the preceding claim, the upper and lower parts of which 90 are formed respectively by the bottom of the brick pan and the top of the oil tanks.

In testimony whereof I have signed my name to this specification in the presence of two subscribing witnesses.

HAROLD E. YARROW.
